DESIGN FOR A TOWEL OR SIMILAR ARTICLE

Daniel J. Faraggi, Brooklyn, N. Y.

Application November 24, 1941, Serial No. 104,281

Term of patent 3½ years

To all whom it may concern:

Be it known that I, Daniel J. Faraggi, a citizen of the United States, and residing at Brooklyn, New York, in the county of Kings and State of New York, have invented a new, original and ornamental Design for a Towel or Similar Article, of which the following is a specification, reference being had to the accompanying drawing, forming part thereof, and in which the figure is a plan view of a towel, showing my new design.

I claim:

The ornamental design for a towel or similar article, substantially as shown,

DANIEL J. FARAGGI.
